DISH MOP

Harry Hertzberg, New York, N. Y., assignor to
 Hertzberg Patents, Inc., New York, N. Y., a corporation of New York

Application May 7, 1937, Serial No. 141,235

8 Claims. (Cl. 15—122)

This invention relates to mops and more particularly to that type of mop known as dish mops and used for cleaning pots, pans and dishes in a kitchen under running hot water.

5 It is an object of the present invention to provide a mop of this kind which is of simple and rigid construction and which combines with the mop material a receptacle for soap or the like for supplying soap suds thereto.

10 It is a further object of the invention to provide a mop of this kind which has a handle firmly and rigidly connected to the mop material and centrally secured in the soap receptacle.

15 It is still another object to provide an implement of this kind in which the handle, mop material and soap receptacle form a unitary structure.

It is a further object to protect the hands of the persons washing dishes from hot soap suds.

20 It is still another object to provide a simple and rigid device for the above purpose which can be sold at a very reasonable price.

It is a further object to provide a device of this kind which can be handled successfully by anyone without further instructions and will give complete satisfaction.

25 With these and other objects in view the advantages of the invention will be apparent from the description thereof taken in connection with the accompanying drawing in which—

30 Fig. 1 is a front view of a mop embodying the invention.

Fig. 2 is an enlarged detail section on the line 2—2 of Fig. 3.

35 Fig. 3 is a horizontal section on line 3—3 of Fig. 2.

Referring to the drawing, 10 represents mopping material consisting preferably of cotton cords bent upon themselves at their middle. The 40 cotton cords 10 are held together to form a mop by a ring shaped loop 11 of wire, which wire encircles the mop cords at their center. The free ends of the wire are twisted about each other to form a tang 12. This tang is held in an axial aperture 13 in a handle 14 into which it is tightly connected.

45 The lower end of the handle is covered by a cylindrical receptacle 15 of sheet metal which has an upwardly tapering conical bottom 15a provided at its upper end with a cylindrical depression having an annular wall 15b and a horizontal bottom 15c through an axial aperture of which tang 12 passes into aperture 13 of handle 14. The depression 15b—15c holds handle 14 in axial alignment with receptacle 15 and rigidly connected

thereto by means of tang 12 and loop 11 and cement 13a. The cylindrical wall of receptacle 15 is provided at its upper end with a peripheral thread which is engaged by a similar thread on a hemispherical cap 16 which is slidably mounted 5 on the upper part of handle 14 by a central opening in its top which is preferably provided with an integral guide ring 16a. Perforations 17 are provided as shown in cap 16 and at 18 at the lower periphery of receptacle 15. 10

When in use this receptacle 15 is preferably filled with soap or soap chips which provide the mop material below with soap suds when hot water flows into receptacle 15 through the perforations 17 in cap 16 and out of the receptacle 15 15 through the perforations 18 as suds into the mop material 10.

It will be clear from the foregoing description that the soap receptacle 15 with cap 16 are solidly supported on handle 14 against longitudinal or 20 lateral displacement and also that the cap 16 is independently guided on a cylindrical part of handle 14 to bring the threads thereon in alignment with the threads on receptacle 15 for closing. 25

When this device is to be used, the cover or cap 16 is first removed from cup or receptacle 15 by unscrewing it therefrom, sliding it upwardly on handle 14 and removing it therefrom if desired. The receptacle 15 is then filled with small chips 30 of soap or preferably soap flakes whereupon the cap or cover is replaced on the cup, and the device is ready for washing dishes and the like.

The improved mop has been shown only in its preferred form and it should be understood that 35 changes in details may be made without departing from the principle of the invention and I therefore desire to be limited only by the state of the prior art and the appended claims.

It will be understood that in place of the cords 40 10 any other suitable material may be used, such as, tampico fibre, bristle, hair or crimped brass wire, sponge rubber and steel wool or other abrasive material.

I claim:

1. A mop having a handle, a wire loop having a tang portion fastened to said handle, mop material held by said loop, a cup for soap positioned around said handle, a cover on said cup and around said handle, said cover having a central 50 aperture to form a guide for positioning same on said handle, the bottom of said cup having a central aperture to permit passage of the tang therethrough whereby bending stresses are carried by said handle without stressing said cup. 55

2. In a mop, a handle, a wire loop having a tang portion, mop material held by said loop, a cup for soap, a cover for said cup, said cup having an aperture substantially the size of the cross-section of the tang and adapted to cooperate with said tang to prevent lateral motion of the cup and with said handle to prevent longitudinal motion of said cup, and said cover being adapted to be guided by said handle into its place on said cup.
3. In a device of the kind described, a handle, a perforated receptacle adapted to contain soap, the bottom of said receptacle forming a seat for the handle, a mop swab adjacent the bottom of said receptacle, a cap forming a top thereon, and a tang on said handle holding said swab, said receptacle, and said cap in axial alignment with each other.
4. A mop comprising mop material of fibrous texture, a looped wire holding said material, the end portions of said wire forming a tang, a handle holding said tang within an axial aperture at one end of said handle and a cup shaped receptacle fastened on said handle by said tang, the bottom of said receptacle forming a seat for the handle.
5. A mop comprising cords, a wire forming a loop surrounding said cords, end portions of said wire forming a tang, a handle having one end engaging said tang, a cup shaped receptacle mounted on said handle by means of a tang and a perforated cover on said receptacle, said cover having a central opening to guide said cover to closed position on said receptacle and a recess in the bottom of said receptacle forming a seat for said handle.
6. A mop comprising a handle, mopping mate-

rial fastened to the end of the handle, a cup member secured between the end of the handle and the mopping material, said cup being formed with apertures and with a seat for said handle and a cover for said cup, said cover having a central aperture to coact with said handle to guide said cover to closed position on said cup.

7. A mop comprising a handle having an axial bore, mopping material at the end of said handle, a cup shaped member between said handle and mopping material and provided with perforations and with a seat for said handle, a tang member embedded in said axial bore and adapted to join said handle, mopping material and cup together in axial alignment and a cup cover having a central opening adapted to co-act with the handle to guide said cover into closed position on said cup.

8. A mop comprising a handle having an axial bore, mopping material at the end of said handle, a cup shaped member between said handle and mopping material, said cup having a central depressed portion provided with a central opening in alignment with said axial bore, the end of said handle being seated in said depressed portion, said cup being provided with perforations aligned with the mopping material, a tang passing through the mopping material, the central opening in the cup and into the axial bore of the handle for fastening the handle, cup and mopping material together and a cover for said cup, said cover having a central opening adapted to coact with said handle to guide said cover to closed position on the cup.

HARRY HERTZBERG. 35
